UNITED STATES PATENT OFFICE.

JAMES CRAWFORD POTTER, OF PROVIDENCE, RHODE ISLAND.

SCREW CAP OR CLOSURE.

SPECIFICATION forming part of Letters Patent No. 743,189, dated November 3, 1903.

Application filed April 30, 1903. Serial No. 154,912. (No model.)

To all whom it may concern:

Be it known that I, JAMES CRAWFORD POTTER, a citizen of the United States, and a resident of Providence, in the county of Providence and State of Rhode Island, have invented certain new and useful Improvements in Screw Caps or Closures, of which the following is a specification.

The subject of the present invention is an improved screw-cap for nozzles, and has reference more particularly to the type of cap having a chain connection with a fixed part for insuring the convenient retention of the cap when detached from the nozzle and preventing said cap from becoming lost or mislaid.

The more prominent object of the invention is to obtain a highly-secure engagement with the cap in a simple, efficient, and comparatively inexpensive manner.

With the above and other purposes in view the invention comprises generally the feature of a supplemental or auxiliary section permanently secured on the top of the cap and carrying the eye connection for the chain, said section serving to greatly strengthen said connection as well as reinforce the cap.

There are other important features and details connected with the novel cap, which, as well as those alluded to, are clearly set forth in the subsequent extended description.

In the accompanying drawings, forming part of this specification, Figure 1 is a fragmental view, partly sectioned, of the upper portion of a sheet-metal can having my invention combined therewith. Fig. 2 is a vertical sectional view of the cap disclosed in Fig. 1 and representing the cap on a larger scale. Fig. 3 is a plan view of said cap. Fig. 4 is a view somewhat similar to Fig. 2, but illustrating a cap embodying another form of my invention.

Similar reference characters are employed to designate corresponding parts throughout the several figures of the drawings where they occur.

In providing screw closures or caps for nozzles in many instances it is desirable to permanently attach the cap by a chain to some fixed portion, so that when the cap is unscrewed from the nozzle it will remain in such proximity as to be always handy when it is

to be again screwed in engagement with the nozzle. Generally the class of articles with which said nozzles and caps are employed—
55 as, for instance, oil-cans, &c.—is such that the caps are usually pressed or spun up from a comparatively soft sheet metal, such as zinc or tin, and secured to the top thereof, generally by soldering, is an eye, to which
60 one end of the connecting-chain is attached. Inasmuch as the cap is frequently subjected to considerable strain and pull, there is a liability of the eye being pulled from the cap, and this will be true to some extent even if
65 the eye is not soldered to the top, but is passed through an opening in the cap-top and engaged at the under side of the latter.

By my invention I obviate the objections noted and provide a durable and efficient
70 chain connection which besides being extremely simple will serve to greatly reinforce and strengthen the cap.

Referring now more especially to Figs. 1 to 3, inclusive, A indicates the upper portion of
75 an oil-can, it not being deemed necessary to illustrate the ears and bail. The sloping top A' of this can has a central opening presented by a short tapering flange a, to which the overlapping base b of the nozzle B is secured
80 by soldering. The nozzle embodies coarse screw-threads pressed or spun therein in a manner well known.

The cap C comprises the cylindrical body c, with threads suitable for engaging those of
85 the nozzle, the cap being formed of one piece of metal and including the closed top c'. Mounted on the top c' of the cap is a disk or circular section D, which is permanently secured to the top, preferably by soldering, said
90 section being slightly dished on its under side, providing a shallow space d between the top c' and said section. The latter is centrally provided with a small perforation through which pass the free portions e e, constituting
95 the shank of a circular wire eye E, the terminals e' of the shank portions being oppositely bent to lie within the space d, and thereby serve to securely attach the eye to the cap, but permit its swiveling movement relative
100 thereto. It will be convenient, of course, to engage the eye with the section D before securing the latter in position upon the cap-top. Inasmuch as this type of cap is ordinarily

made of a soft sheet metal, such as zinc or tin, I prefer to make the disk or section D of a metal more durable and rigid in character—as, for instance, brass.

5 Manifestly the chain F, which is engaged at one end with the eye E, can have its other end permanently attached to any suitable fixed part, according to the particular application of the invention. In Fig. 1 I have represented such permanent attachment as being effected by a small clip f, soldered on the cap-top.

From the foregoing description it will be readily appreciated that a cap and chain connection embodying my invention is not only simple, but extremely strong and comparatively inexpensive. Moreover, the swiveling relation of the eye E prevents the chain from becoming objectionably fouled or twisted.

15 20 It will be readily comprehended that the novel cap and chain connection is equally adapted for service in connection with threaded nozzles in all other instances where the same are employed.

25 In Fig. 4 is disclosed a cap C' embodying another form of the invention. In this arrangement the disk or section E' by being considerably more concaved than is the somewhat similar portion in the previous figures

30 is therefore adapted to be made of a grade of sheet metal somewhat similar to that employed for the cap proper, the increased concavity imparting additional strength, while small openings e² in said section E', adjacent

to the cap-top c², prevents any tendency to 35 the formation of a vacuum beneath said section, besides facilitating its being brought into proper shape during manufacture.

I do not wish to be understood as limiting myself to either of the precise arrangements 40 shown and described, but reserve the right to all such modifications as may be fairly within the scope of my invention.

Having now described my invention, what I claim as new, and desire to secure by Letters 45 Patent, is—

1. A screw cap or closure of the character described, comprising a body and top of highly-ductile metal, and an independent section of a more rigid metal secured fixedly to said top, 50 and extending over the major surface thereof, and a vertically-projecting eye connected to said section.

2. A sheet-metal screw cap or closure provided with an independent dished section secured to its top, and forming with the latter a space d, and a chain-engaging eye having its shank portions passing through said section and oppositely bent to lie within the space d.

Signed at Providence, in the county of Providence and State of Rhode Island, this 25th day of March, A. D. 1903.

JAMES CRAWFORD POTTER.
